DISPLAY CARRIER

Vernon F. Detweiler, Lansdale, Pa.

Application November 7, 1949, Serial No. 125,985

7 Claims. (Cl. 224—48)

1

This invention relates to display carriers, and more particularly to display carriers having a plurality of shelves that are adapted to be extended so as to more fully display any wares that may be on the lower shelves.

Heretofore the majority of display carriers used by vendors going from door to door usually comprise only one shelf on which articles may be placed for display purposes. The few display carriers that have been made with extendable shelves are either too bulky and complicated to be successfully used commercially or else they have a tendency to sag after being in use for a while so that the top shelf rests upon the goods on the lower shelf.

With the foregoing in mind, the principal object of this invention is to provide a novel display carrier having a plurality of shelves which are relatively extendable, that is sturdy in construction and will not become distorted after being used for a while.

Another object of this invention is to provide a novel device of the type described above that is light in weight and may be easily handled.

A further object of this invention is to provide a novel display carrier having the above-mentioned characteristics, that may be manufactured easily and cheaply and is dependable in use and operation.

These and other objects of the invention and the various features and details of the construction and operation thereof are hereinafter fully set forth and described with reference to the accompanying drawings, in which:

Fig. 1 is a perspective view of the display carrier in a carrying position;

Fig. 2 is a perspective view of the display carrier resting on the ground and having its lower tray extended;

Fig. 3 is a side elevational view of a person holding the display carrier in an extended position;

Fig. 4 is a side elevational view of the display carrier in the extended position as shown in Fig. 2;

Fig. 5 is a sectional view taken along the line 5—5 in Fig. 1;

Fig. 6 is a sectional view taken along the line 6—6 in Fig. 1; and

Fig. 7 is a sectional view taken along the line 7—7 in Fig. 1.

The display carrier shown in the drawings consists of two trays, the lower one of which may be thrust forwardly or projected with respect to the upper tray so as to display completely the

goods carried on both of the trays. Referring more particularly to the drawings, reference numeral 10 designates generally a display carrier made according to the invention and comprising upper and lower trays 11 and 12, respectively. The trays 11 and 12 are rectangular in shape and have flat portions 11a and 12a of substantial area, and upturned edges 11b and 12b. Interconnecting the upper and lower trays at each end of the carrier is a pair of parallel links 13 and 14 which have their opposite ends pivotally connected to the upper and lower trays 11 and 12, respectively, in the relation shown in the drawings.

15 Thus, the links 13 at opposite ends of the carrier have their lower ends pivotally connected to the lower tray 12 centrally of the end of the tray as at 15 and have their upper ends pivotally connected to the end of the upper tray 11 adjacent 20 the front or forward edge thereof as at 16. The links 14, on the other hand, have their upper ends pivotally connected to the upper tray 11 at a point centrally of the ends thereof as at 17 and the lower ends of said links are pivotally connected to the ends of the lower tray 12 adjacent the back or rearward edge thereof as indicated at 18.

25 By this construction it will be observed that the lower tray 12 is connected to the tray 11 in a manner to permit the lower tray to be moved relative to the upper tray by a swinging motion between the position shown in Fig. 1 wherein the two trays are relatively superimposed and in a position such as shown in Figs. 2, 3 and 4 wherein the lower tray 12 is extended or projected forwardly or in front of the upper tray 11.

30 In the relatively superimposed position of the trays shown in Fig. 1 of the drawing, the upper tray is arranged to rest upon and be supported 40 by upstanding legs 19 which are secured centrally of the opposite ends of the lower tray 12 and have their upper end portions bent inwardly as indicated at 19a to provide a surface for engagement by the upper tray 11. By this construction the tray 11 is positively supported in a fixed position above and clear of articles on the lower tray 12.

45 The several pivotal connections are substantially the same at the different points throughout the display carrier 10. The fastening means at 16 is shown in Fig. 6. It consists of a bolt 20 secured to the upper tray 11 by a lock nut 21. A bushing 22 is positioned in the link 13 and friction washers 23 are positioned on either side of the link 13 to allow the link 13 to be easily rotated

with respect to the tray 11 but still held tight enough to prevent any outward motion of the link 13 with respect to the tray 11. An elastic stop nut 24 is threaded on the bolt 21 to hold these various parts together and by periodically tightening the nut 24 the assembly may be maintained relatively tight. The fastening means at 18 is shown in Fig. 7. In this case two links are pivotally connected to the tray 12. This construction is similar to the fastening means shown in Fig. 6 except, to accommodate the extra link, the bushing 22a is of greater length and three friction washers 23 are employed instead of two.

A semi-circular handle 25 is connected across the center portion of the upper tray 11 to be used for carrying the display carrier 10. The handle 25 may be made from a piece of tubing which is flattened at each end 25a for easy attachment to the upturned edges 11b of the tray 11 as shown at 26 and 27.

Suitable means for actuating the lower tray 12 with respect to the upper tray 11 is provided in the form of a generally U-shaped bracket 28 having a flat central portion 29 and legs 30 that have their free ends pivotally connected to the upper tray 11 at the point of connection thereto of the links 14. The bracket 28 is connected to the lower tray 12 by link 31 which is pivotally connected to the lower tray at the points 18 and fixedly attached to the leg 30 of the bracket 28 by suitable fastening means 32. Thus it can be seen that the lower tray 12 may be moved forward with respect to the upper tray 11 by rotating the bracket 28 about the point 17.

It will be observed that when the trays are in the relatively superimposed position as shown in Fig. 1 the central portion 29 and legs 30 of the bracket 28 are in an adjoining relationship with the rear and side edges 11b of the upper tray 11. The bracket 28 is held in this position by a spring catch 33 fixedly secured to the central portion of the rear edge 11b of the upper tray 11. A handle 34 is provided centrally of the portion 29 to facilitate disengagement thereof from the catch 33. The catch 33 is provided with a horizontally projecting top portion 35 which limits upward travel of the bracket 28.

To extend the lower tray 12 with respect to the upper tray 11 the handle 34 is grasped and pulled outward to disengage the bracket 28 from the spring catch 33 and then moved downward with a clockwise rotation about the pivot point 17. To return the trays to the carrying position the handle 34 is moved in a counterclockwise motion about the point 17.

The principal use of this display carrier is for vendors going from door to door selling their goods, and may be used for practically any kind of small merchandise. This display carrier may either be set on the ground in the opened position as shown in Fig. 2, or it may be held by the vendor in the open position by holding the carrier handle 25 in one hand with the upper tray against the body and the bracket handle 34 resting against one leg as shown in Fig. 3.

While certain embodiments of this invention have been illustrated and described herein, it is not intended to limit the invention to such disclosures, and changes and modifications may be made therein and thereto within the scope of the following claims.

I claim:

1. A display carrier comprising upper and lower trays arranged normally in superimposed rela-

tion, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, a bracket for actuating the lower tray pivotally connected to the upper tray and to said lower tray, said bracket having a portion arranged in the superimposed relation of the trays to lie laterally adjacent the upper tray, and latch means secured to the upper tray and releasably engageable by said bracket portion to retain the trays in said superimposed relation.

2. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, upstanding legs on the lower tray arranged in said superimposed relation of the trays to engage and support the upper tray, a bracket for actuating the lower tray pivotally connected to the upper tray and to said lower tray, said bracket having a portion arranged in the superimposed relation of the trays to lie laterally adjacent the upper tray, and latch means secured to the upper tray and releasably engageable by the intermediate bracket portion to retain the trays in said superimposed relation.

3. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, a bracket for actuating the lower tray pivotally connected to the upper tray and having a portion arranged in the superimposed relation of the trays to lie laterally adjacent the upper tray, links pivotally connecting the bracket to the lower tray, and latch means secured to the rearward edge of the upper tray and releasably engageable by the intermediate bracket portion to retain the trays in said superimposed relation.

4. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, upstanding legs on the lower tray arranged in said superimposed relation of the trays to engage and support the upper tray, a bracket for actuating the lower tray pivotally connected to the upper tray and having a portion arranged in the superimposed relation of the trays to lie laterally adjacent the upper tray, links pivotally

connecting the bracket to the lower tray, and latch means secured to the upper tray and releasably engageable by the intermediate bracket portion to retain the trays in said superimposed relation.

5. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, a bracket for actuating the lower tray pivotally connected to the upper tray and to said lower tray, said bracket having a portion arranged in the superimposed relation of the trays to lie laterally adjacent the upper tray, a spring catch secured to the upper tray and releasably engageable by the bracket portion, and a handle on said bracket to disengage the same from the catch and actuate the bracket and lower tray to project the latter into forwardly stepped relation with respect to the upper tray.

6. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, upstanding legs on the lower tray arranged in said superimposed relation of the trays to engage and support the upper tray, a bracket for actuating the lower tray pivotally connected to the upper tray and to said lower tray, said bracket having a portion arranged in the superimposed relation of the trays to lie laterally adjacent the upper tray, a spring catch secured to the rearward edge of the upper tray and re-

leasably engageable by the intermediate bracket portion, and a handle on said bracket to disengage the same from the catch and actuate the bracket and lower tray to project the latter into forwardly stepped relation with respect to the upper tray.

7. A display carrier comprising upper and lower trays arranged normally in superimposed relation, parallel links pivotally interconnecting said trays and having their connections to the upper tray disposed substantially forward of their connections to the lower tray to provide swinging movement of the lower tray relative to the upper tray to and from said superimposed relation thereof and a position in which the lower tray is projected forwardly in stepped relation to the upper tray, a bracket for actuating the lower tray pivotally connected at its opposite ends to the upper tray and having a portion arranged in the superimposed relation of the trays to lie laterally adjacent the upper tray, links pivotally connecting the bracket to the lower tray, a spring catch secured to the rearward edge of the upper tray and releasably engageable by the intermediate bracket portion, and a handle on said bracket to disengage the same from the catch and actuate the bracket and lower tray to project the latter into forwardly stepped relation with respect to the upper tray.
